(57) **CLAIM**

The ornamental design for a dispenser, as shown and described.

DESCRIPTION

FIG. 1 is a perspective view taken from the top, front, and left side of the dispenser of the present invention;

FIG. 2 is a left side elevational view of the dispenser of FIG. 1;

FIG. 3 is a right side elevational view of the dispenser of FIG. 1;

FIG. 4 is a bottom plan view of the dispenser of FIG. 1;

FIG. 5 is a top plan view of the dispenser of FIG. 1;

FIG. 6 is a front elevational view of the dispenser of FIG. 1; and,

FIG. 7 is a rear elevational view of the dispenser of FIG. 1.

The broken line showing of portions of the dispenser is included for the purpose of illustrating environmental structure and forms no part of the claimed design.
